Des. 67,863

UNITED STATES PATENT OFFICE.

WESLEY E. WHELESS, OF SHREVEPORT, LOUISIANA.

DESIGN FOR A CLOCK CASE.

Application filed May 31, 1924. Serial No. 9,759. Term of patent 3½ years.

To all whom it may concern:

Be it known that I, WESLEY E. WHELESS, a citizen of the United States, residing at Shreveport, in the parish of Caddo and State of Louisiana, have invented a new, original, and ornamental Design for Clock Case, as shown in the accompanying drawing, and described in the following specification.

Fig. 1 designates the front elevation view of the new, original and ornamental design herewith claimed.

Fig. 2 illustrates a side elevation view thereof.

I claim:

The ornamental design for a clock case as shown.

WESLEY E. WHELESS.
